UNITED STATES PATENT OFFICE.

RICHARD MÜLLER, OF NORWALK, CONNECTICUT.

UMBRELLA-COVERING.

1,089,857.

Specification of Letters Patent. Patented Mar. 10, 1914.

Application filed September 30, 1911. Serial No. 652,090.

To all whom it may concern:

Be it known that I, RICHARD MÜLLER, a subject of the Emperor of Germany, residing at Norwalk, in the county of Fairfield 5 and State of Connecticut, have invented certain new and useful Improvements in Umbrella-Coverings, of which the following is a full, clear, and exact description.

This invention relates to fabric coverings 10 for umbrellas and the like, and more particularly to a novel binding or edging for fabrics of this description.

The invention has for its object the production of an edging or tape of improved 15 wearing qualities and appearance, and one, moreover, which materially reduces the cost of production of the fabric as a whole.

These and other objects of my invention 20 will be hereinafter set forth and more particularly pointed out in the appended claims.

In the drawings which form a part hereof and in which like reference characters designate like parts throughout the several views: Figure 1 shows a width of fabric of the 25 character in question before the same has been severed preparatory to forming my novel tape thereon. Fig. 2 shows a fragment of such fabric after it has been severed from the body of the material, and Fig. 3 30 shows a section of the novel tape, drawn to an enlarged scale.

In the manufacture of the better grades of umbrella coverings it has been common heretofore to weave the covering in narrow 35 looms and of just the width required, the weft threads being turned at the edges around the outermost warp threads in the usual manner; an edging or tape-like weave being provided along the respective lateral 40 edges of the fabric, which edgings are by reason of the turned weft threads quite well adapted to withstand wear. For convenience and cheapness of manufacture, however, it is preferable to weave the covering 45 fabric of two or more times the width required; but this entails severing the woven material lengthwise with consequent cutting of the weft. Further the taped edge would, in the absence of the provision of a band of 50 tape-like material through the body of the fabric, be found only upon one edge of the severed strips. In order therefore to provide an edging for the other side of the fabric it is necessary to weave a tape-like 55 band or bands lengthwise directly through

the body of the fabric, which bands when the material is cut may present substantially the same appearance as the true edging formed by the loom. Now as the weft threads must be severed in the manner above 60 stated, these supplemental edgings, formed from the intermediate bands, will ravel unless some means be provided for guarding thereagainst, and I have found that a 65 slightly and exceedingly durable binding may be formed in the manner which will now be described, having reference to the drawings.

In Fig. 1 I have shown a double width of fabric of the type in question formed in a 70 wide loom, the body of the fabric being designated 1 and being provided with finished selvage edges 2 during the course of the weaving. Selvage or tape-like bands 3 extend, in this instance, substantially centrally and longitudinally of the sheet, which bands are woven to have substantially the same appearance as the selvage edges 2. Between the bands 3 is a belt or section of fabric 4 which may, if desired, be woven in 80 analogous fashion to the body parts 1, this section 4 preferably having a width at least equal to the combined widths of the bands 3, or in other words, the width a of the band 4 is double the width b of the band 3, and 85 the width b of a band 3 is preferably the same as that of a tape 2. After the fabric has been woven it is severed longitudinally thereof, in this instance along the median line of the belt 4. At this stage of the 90 process of manufacture the fabric will appear as shown in Fig. 2; the severed portion 4' of the band 4 being shown at the right hand edge of the fabric strip. The narrow band 4' is now folded over upon the 95 band 3 in the manner shown in Fig. 3, as for instance by passing the strip or sheet of fabric through suitable rolls, and the folded parts 3 and 4' are firmly secured together by means of adhesive material. 100 Thin rubberized paper or fabric forms a very convenient adhesive material for this purpose, a strip of this substance of approximately the width b being introduced between the folded edge 4' and the band 3 when the 105 edge 4' is being folded over upon said band 3; the material being heated sufficiently to render the rubberized fabric adhesive while pressure is being applied upon the folded portions of the fabric. In this way a taped 110

edge, broadly designated 6, is made which is integrally united to the body of the fabric 1, and which when viewed in the direction of the arrows presents substantially the same appearance as the tapered edge 2; but the taping 6 is even more substantial than the said edge 2, and it is practically impossible for it to ravel, no free weft ends being exposed at the fold 7.

- 10 As viewed from below, the fabric, for all intents and purposes, appears to be of uniform weave from the body 1 to the extreme edge or fold 7, for since the fabric is thin the inwardly directed edge 8 of the band 4' will scarcely be noticeable. The covering thus produced is attractive in appearance, durable, and may furthermore be produced at a minimum of expense since the cost of the extra width of material 4' which is 20 folded over is but slight, and the operation of adhesively securing said material while folding the same is practically inconsiderable. The appearance of the tape or edging is also improved when viewed from the inside, when the umbrella is raised, since tape constructed in accordance with the present invention is more dense, and opaque to light, than woven tape as heretofore constructed.

Having described my invention, I claim:

1. A fabric for umbrella coverings comprising a woven fabric having selvages and a pair of tape-like bands woven therein, said fabric being adapted to be severed intermediate said pair of bands and having a strip of fabric attached to each of said bands, said strips being adapted to be folded over the bands to form a smooth selvage-like edge.

2. As an article of manufacture, a fabric for umbrella coverings having a selvage and a plurality of tape-like bands woven therein, said fabric being adapted to be cut into determined widths with tape-like bands spaced from each of the severed edges, the material between the band and the severed edges being adapted to be folded over and adhesively secured to the band to form a selvage-like edge of sufficient strength to prevent the tearing of the fabric when stretched.

In witness whereof, I subscribe my signature, in the presence of two witnesses.

RICHARD MÜLLER.
